F. L. WILLARD,
 ELECTRIC CONTROLLING DEVICE.
 APPLICATION FILED OCT. 2, 1905.

2 SHEETS-SHEET 2

UNITED STATES PATENT OFFICE.

FREDERICK L. WILLARD, OF BROOKLYN, NEW YORK, ASSIGNOR OF ONE-HALF TO GEORGE WEIDNERMAN, OF NEW YORK, N. Y.

ELECTRIC CONTROLLING DEVICE.

No. 817,945.

Specification of Letters Patent.

Patented April 17, 1906.

Application filed October 2, 1905. Serial No. 280,922.

To all whom it may concern:

Be it known that I, FREDERICK L. WILLARD, a subject of the King of Great Britain, residing at Brooklyn, in the county of Kings and State of New York, have invented certain new and useful improvements in Electric Controlling Devices, of which the following is a specification, such as will enable those skilled in the art to which it appertains to make and use the same.

The object of this invention is to provide a controlling device for use in connection with electric power apparatus, such as motors and the like, for use in connection with elevators and machinery of various kinds and classes, a further object being to provide a controlling device which may be used in connection with illuminated signs whereby the separate portions or characters thereof may be operated either singly or together for predetermined intervals and be automatically deenergized, a further object being to provide a controlling device of the class described by means of which the resistance in an electrical circuit may be gradually reduced and when entirely overcome the said controlling device may be maintained in the last-named position indefinitely and without the expenditure of an appreciable amount of electrical energy; and with these and other objects in view the invention consists in an electrical controlling device of the class hereinabove described and claimed.

The invention is fully disclosed in the following specification, of which the accompanying drawings form a part, in which the separate parts of my improvement are designated by suitable reference characters in each of the views, and in which—

Figure 1 is a front elevation of the mechanical arrangement of my controlling device; Fig. 2, a side elevation thereof; Fig. 3, a partial section on the line 3-3 of Fig. 1; Fig. 4, a diagrammatic view of my apparatus when arranged for use in connection with elevators and the like; Fig. 5, a diagrammatic view thereof as arranged for use in connection with the continuously-operating machinery and the like, and Fig. 6 a diagrammatic view of my apparatus when used in connection with illuminated signs.

In the drawings forming part of this specification I have shown a plate *a*, preferably composed of slate or other non-conductive

material, upon which is placed a casing *a*² and upon the outer face of which is mounted a base-plate *a*³, also composed of slate or other non-conductive material, and within the casing *a*², although not shown in the drawings, I arrange a suitable resistance, as diagrammatically represented in Figs. 4, 5, and 6.

Pivotedly mounted on the base *a*³ to suitable supports *b* are a plurality of arms *b*², *b*³, *b*⁴, and *b*⁵, each of which is provided in the upper end thereof with a spring-operated plunger *b*⁶ and with a limiting-stop *b*⁷ at the lower end thereof, and at a predetermined point with a lug or projection *b*⁸, composed of non-conductive material, and, as will be seen by reference to Fig. 2 of the drawings, the arms *b*², *b*³, *b*⁴, and *b*⁵ are adapted to move into the position indicated by dotted lines, but normally rest in and return to the position shown in full lines because of the position of the pivotal point thereof and gravity, and each of the arms is provided with an electrical conductor *b*⁹, which communicates the plunger *b*⁶ with the corresponding support *b* and insures electrical communication therewith at all times.

Mounted upon the base-plate *a*³ and in line with the corresponding arms *b*², *b*³, *b*⁴, and *b*⁵ are a plurality of electromagnets or solenoids *c*, *c*², *c*³, and *c*⁴, and secured to the base-plate *a*³ and in a position where they are adapted to be operated by the corresponding lugs *b*⁸ of the arms are a plurality of circuit-breakers *d*, *d*², and *d*³, which are normally in electrical communication with each other, as shown in the structural drawing Fig. 3 and as diagrammatically shown in Figs. 4, 5, and 6, by means of electrical conductors *d*⁴ and in the arrangement, as shown in Figs. 1, 2, 3, and 4, the number of circuit-breakers is one less than the number of arms, this arrangement, as previously stated, being for use in connection with elevators and the like which are operated for short periods only.

Mounted in the base-plate *a*³ in positions where they are adapted to be placed in communication with the plungers *b*⁶ are a plurality of contacts *e*, *e*², *e*³, and *e*⁴, before and between which are arranged suitable resistance-coils *e*⁵, *e*⁶, *e*⁷, and *e*⁸, said resistance-coils being in electrical communication with one of the main wires *f*, and the contact *e*⁴ is in electrical communication with a main wire *g*, and

in the arrangement shown in Fig. 4 the motor g^3 is provided with a shunt-field g^2 , and wires f and g are provided with a switch g^4 , which when closed is adapted to complete a circuit through the wires f and g , motor g^3 , and the resistance-coils and contacts hereinbefore mentioned.

In the arrangement shown in Fig. 4 the electromagnet e is in electrical communication with the wire g by means of the conductor h , and said electromagnet or solenoid e is also in direct electrical communication with the circuit-breaker d , and by means of a conductor h^2 is in communication with the solenoid c^2 , which is also in communication with the circuit-breaker d^3 and with a solenoid c^3 by means of a conductor h^3 , and the solenoid c^3 is in electrical communication with the circuit-breaker d^3 and with a solenoid c^4 , which 20 in turn is in electrical communication with a conductor d^5 , which connects the circuit-breaker d^3 or one of the members thereof with the wire g . It will therefore be seen that when the switch g^4 is closed a circuit is formed through the wire f , the resistances e^5 e^6 , &c., the contacts e e^2 , &c., the conductors g and d^5 , circuit-breakers d^3 , d^2 , and d , solenoid c , conductor h , and main wire g , and the solenoid c^4 being thereby energized attracts the 30 arm b^2 and draws the same into the vertical position indicated in dotted lines in Fig. 2.

When the arm b^2 is drawn into its vertical position, the upper end thereof bears against the contact e , and the lug or projection b^3 of the arm b^2 opens the circuit-breaker d , and a circuit is thus closed through the main wires f , arm b^2 , contact e , resistance-coils e^6 , e^7 , and e^8 , main wire g and motor g^3 , and the resistance-coil e^9 is thereby cut out and the motor g^3 is energized and a supplemental circuit is formed through the conductor d^5 , circuit-breakers d^3 and d^2 , solenoids c^2 and c , and conductor h to the wire g , and the solenoid c^2 is energized, thereby attracting the arm b^3 , which when in its vertical position cuts out the resistance-coil e^9 and opens the circuit-breaker d^2 , and this places the solenoid c^3 in the supplemental circuit just described because of the fact that the circuit-breaker d^2 had been open.

When the solenoid c^3 is energized, the arm b^3 is attracted thereby, and when in its vertical position the resistance-coil e^7 is cut out and the circuit-breaker d^3 is opened, and the solenoid c^4 is thus made a part of the supplemental circuit referred to, and the arm b^5 is thereby moved to its vertical position and the resistance-coil e^8 is thereby cut out, and a main circuit is formed through the wire f , arm b^5 , contact e^4 , wire g , and motor g^3 , and the motor g^3 is receiving the highest possible potential, and at the same time a supplemental circuit is formed through the solenoids and the resistance-coils which is powerful enough to hold the arms b^2 b^3 , &c., in

their vertical positions as long as the switch g^4 is in its closed position, and it is for this reason that the arrangement just described is adapted for use in elevators and the like where but a short period of operation of the motor g^3 is desired because of the fact of the considerable loss of electrical energy necessary to maintain the arms in their vertical positions.

The arrangement shown in Fig. 5 of the drawings is essentially similar to that shown in Fig. 4 with the exception that connected with the shunt-field g^2 is a conductor i , which forms a supplemental winding of each of the solenoids or electromagnets e e^2 , &c., and in this arrangement I also provide an additional circuit-breaker d^6 , which is connected in the same manner as the circuit-breakers hereinbefore mentioned. The operation during the early stages of this arrangement is precisely the same as that described in Fig. 4, but with this difference, that when the arm b^5 is attracted to its vertical position the supplemental circuit-breaker d^6 is open, thereby cutting out all of the solenoids as well as all of the resistance-coils and a small amount of electrical energy passes through the shunt-field and the supplemental windings of the solenoids, this amount of energy being just sufficient to hold the arms in their vertical positions, and it will be seen that this arrangement is adapted for use in connection with continuously-operated machinery or the like, because of the fact that a very small amount of electrical energy is necessary to retain the parts in their operative or closed positions.

In Fig. 6 of the drawings I have shown the apparatus adapted for use in connection with illuminated signs, four letters of said sign being shown—namely, A B C D—which are connected with the main wire f and with the corresponding contacts e , e^2 , e^3 , and e^4 , and in this arrangement I employ a number of circuit-breakers equaling the number of arms, and when the switch g^4 is closed a circuit is formed through the wire f , circuit-breakers d^6 , d^3 , d^2 , and d , solenoid c , and wire g , and the solenoid c being energized attracts the arm b^2 and a circuit is then formed through the arm b^2 , contact e , letter A, and wires f and g , and this operation of the arm b^2 , operating the circuit-breaker d , throws the solenoid c^3 into action, which, attracting the arm b^3 , places the letter B in electrical communication and energizes the lights therein, and the arm b^3 , opening the circuit-breaker d^2 , operates the arm b^4 , thereby illuminating the letter C, and as the circuit-breaker d^3 has been opened by the arm b^4 the solenoid c^4 is thrown into action, which attracts the arm b^5 , and the circuit is then closed through the letter D, which is illuminated, but only for a brief interval, for the reason that the circuit-breaker d^6 , being open, breaks the main circuit.

cuit, and all of the arms return to their normal positions, and when the circuit-breaker d^e returns to its normal position the operation just described with reference to all of the letters A, B, C, and D is repeated, and it will therefore be seen that the letters are illuminated consecutively for but a brief period of time and the flashing effect desired in illuminated signs is obtained.

10 It will therefore be seen that my invention consists of magnetically-operated arms, adapted to cut out a plurality of resistance-coils consecutively or to illuminate a plurality of characters consecutively and for brief periods of time, and although I have shown my solenoids connected with both sides of the armature-circuit it will be understood that they may in some cases be connected direct with the line independent of the armature-circuit, and various changes in and modifications of the mechanical arrangement shown and described, as well as of the electrical arrangement, may be made without departing from the spirit of my invention or

15 sacrificing its advantages.

20 The controlling devices for the electric-sign displays herein described are not claimed in this case, but are made the subject of a divisional application filed February 14, 1906, Serial No. 301,034, and the circuit-

25 breaking devices described are also not claimed herein, but are made the subject of a divisional application filed February 14, 1906, Serial No. 301,033.

Having fully described my invention, what I claim as new, and desire to secure by Letters Patent, is—

30 In a controller for electrical circuits, a plurality of electromagnets, a plurality of circuit-breakers in electrical communication therewith, an electrical circuit through the main winding of said electromagnets and through said circuit-breakers, a supplemental winding for said electromagnets arranged through the shunt of said first-named electrical circuit and movable members adapted to be operated by the corresponding one of said electromagnets through the main winding thereof and be held in the last-named position through the supplemental winding thereof, substantially as shown and described.

35 In testimony that I claim the foregoing as my invention I have signed my name, in presence of the subscribing witnesses, this 29th day of September, 1905.

FREDERICK L. WILLARD.
